Primary Examiner — Marianne Pandozzi(74) *Attorney, Agent, or Firm* — John K. Buche; Buche & Associates, P.C.(57) **CLAIM**

The ornamental design for a portable keg container, as shown and described.

DESCRIPTION

FIG. 1 is a front perspective view of a portable keg container showing our new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is a front perspective view thereof in open position; and,

FIG. 9 is a left side view thereof.

The broken lines of the Figures illustrate environmental structure and portions of the portable keg container which form no part of the claimed design.
